E. A. Kern,

UNITED STATES PATENT OFFICE.

EMIL A. KERN, OF WEST NEW YORK, NEW JERSEY

POISON-INDICATING BOTTLE.

1,032,610.

Specification of Letters Patent. Patented July 16, 1912.

Application filed April 3, 1912. Serial No. 888,318.

To all whom it may concern:

Be it known that I, EMIL A. KERN, a subject of the German Emperor, residing at West New York, in the county of Hudson 5 and State of New Jersey, have invented certain new and useful Improvements in Poison-Indicating Bottles, of which the following is a specification, reference being had to the accompanying drawings.

10 This invention relates to improvements in poison indicating bottles and has for its primary object to provide a bottle of this type wherein novel means are employed for indicating the character of the contents of the 15 bottle so as to infallibly prevent all liability of a person mistaking the same for a receptacle containing a harmless medicament.

Another object of the invention resides in the provision of a bottle of the above type 20 the neck of which is provided with a self contained illuminant so that the neck portion of the bottle will be illuminated, thus immediately indicating the poisonous nature of the contents of the bottle.

25 With the above and other objects in view the invention consists in the novel features of construction and in the combination and arrangement of parts hereinafter more fully described, pointed out in the claims, and 30 shown in the accompanying drawings in which,

Figure 1 is a side elevation of a poison indicating bottle embodying the present invention; Fig. 2 is an enlarged vertical section of the upper neck portion of the bottle; 35 Fig. 3 is a section taken on the line 3—3 of Fig. 2; and Fig. 4 is an elevation of a slightly modified form of the bottle.

Referring in detail to the drawing, 5 indicates the body of a bottle and 6 the neck thereof. Spurs or projections 7 are molded upon the surface of the body 5, a blank or plain surface portion 8 being provided for the accommodation of poison indicating labels to be pasted thereon.

In the manufacture of the bottle the neck portion thereof is provided with an internal annular chamber 9 which extends substantially the entire depth of the bottle neck.

The upper end of this chamber is closed by 50 the flange or head 10 which is formed upon the neck. The chamber 9 of the bottle neck is adapted to receive a phosphorent or illuminating chemical indicated at 11, and this illuminant projecting the light rays through 55 the transparent glass will clearly disclose the appearance or character of the bottle to the observer so that he will be aware of the contents thereof even before he has grasped the bottle with the hand. In this 60 manner additional precautionary means is provided to effectually eliminate all possibility of error and to disclose to the user the character of the contents of the bottle or receptacle either during the day or night.

In Fig. 4 of the drawing I have illustrated a slightly modified form of the bottle wherein the same is provided upon its body with a spiral rib 12 whereon the spurs or projections 7' are formed. The neck portion of the bottle is constructed in the same manner as the above described and is provided with the illuminating chemical compound.

In the use of a bottle of either form, when 75 the same is grasped by the hand, the spurs or projections upon the body of the bottle will immediately indicate that the same contains a poisonous liquid.

It will of course be obvious that if desired the spurs or projections may be extended upon the neck portion of the bottle. They may also be arranged upon the bottle in various other ways than as described in the present drawing. The invention is susceptible of still further modification within the scope of the appended claims without departing from the essential features or sacrificing any of the advantages thereof.

What I claim is:

1. A bottle having a neck consisting of inner and outer walls forming a chamber therebetween, and a light emitting compound disposed in said chamber, one of said walls being extended over one end of the 95 other wall to entirely close said chamber and permanently confine said compound therein.
2. A bottle having a neck consisting of

inner and outer walls forming a chamber therebetween, and a light emitting compound disposed in and entirely filling said chamber, said inner wall being extended over one end of the outer wall to entirely close said chamber and permanently confine said compound therein.

In testimony whereof I hereunto affix my signature in the presence of two witnesses.

EMIL A. KERN.
